UNITED STATES PATENT OFFICE.

WILLIAM S. WARD, OF PLANTSVILLE, CONNECTICUT, ASSIGNOR OF ONE-HALF TO EDWARD W. TWICHELL, OF SAME PLACE.

DESIGN FOR A BICYCLE CRANK-SHAFT.

SPECIFICATION forming part of Design No. 26,032, dated September 15, 1896.

Application filed July 25, 1896. Serial No. 600,559. Term of patent 14 years.

To all whom it may concern:

Be it known that I, WILLIAM S. WARD, a citizen of the United States, residing at Plantsville, in the county of Hartford and State of Connecticut, have invented and produced a new and original Design for a Bicycle Crank-Shaft, of which the following is a specification, reference being had to the accompanying drawings, in which—

10 Figure 1 is a side elevation of a bicycle crank-shaft, showing my design; and Fig. 2 is an end view of the same, showing that end of the shaft which is the left-hand end in Fig. 1.

15 My bicycle-shaft is formed with three radial arms near one end thereof.

A designates the body of the shaft, which is round in cross-section. At each end there is a short cylindrical portion 3. At the inner

end of one of these cylindrical portions there is a thin hub 4, from which the three arms 8 radiate, as shown. The arms, when viewed as shown in Fig. 2, are tapered from the hub outwardly. A portion of the periphery of the hub 4 shows its circular contour between the 25 arms. The arms are curved sidewise, as at 5, near their outer ends and terminate in plate-like ends 6, with shoulders 7 on each edge at the junction of the said plate-like ends and body of the arms. 30

What I claim is—

The design for a bicycle crank-shaft substantially as herein shown and described.

WILLIAM S. WARD.
